UNITED STATES PATENT OFFICE.

WILLIAM GROVES AND GRANVILLE D. O'DAY, OF MOUNT STERLING, OHIO.

MACHINE FOR WEAVING CROSS-WIRES IN FENCES.

SPECIFICATION forming part of Letters Patent No. 709,540, dated September 23, 1902.

Application filed January 8, 1902. Serial No. 88,821. (No model.)

To all whom it may concern:

Be it known that we, WILLIAM GROVES and GRANVILLE D. O'DAY, citizens of the United States, residing at Mount Sterling, in the county of Madison and State of Ohio, have invented a certain new and useful Improvement in Machines for Weaving Cross-Wires in Fences, of which the following is a specification.

10 Our invention relates to the improvement of machines for weaving cross-wires in wire fences; and the objects of our invention are to provide a simple and convenient machine of this class of superior construction and arrangement of parts, to provide improved means whereby a fast or slow motion may be imparted to the weaver, to provide an improved construction of machine-supporting frame, and to provide improved bearings for 15 the vertical standards of said frame, and to produce other improvements the details of which will be more fully pointed out hereinafter. These objects we accomplish in the manner illustrated in the accompanying drawings, in which—

Figure 1 is a face view of our improved machine. Fig. 2 is a plan view thereof. Fig. 3 is a detail view in perspective of a portion of the swinging gate which we employ in connection with the main supporting-frame. Fig. 4 is an end view of the machine. Fig. 5 is a view in elevation of portions of the horizontal wires of a fence, showing our improved machine-supporting frame engaged therewith. Fig. 6 is a view in elevation of a portion of a fence completed by our improved machine; and Fig. 7 is a view in perspective of a portion of the machine-supporting frame, illustrating the means for locking the same in connection with the horizontal fence-wires.

Similar numerals refer to similar parts throughout the several views.

In carrying out our invention we employ a normally horizontal weaver-bar 1, the outwardly-extending end portion of which is in the form of a suitable handle 2. The opposite and wider end portion of the bar 1 is provided with outwardly-curved upper and lower terminal arms 1^a, which at their extremities 45 connect with a vertical hinge-tube 1^b.

On what we will term the "rear" side of

the bar 1 is provided a projecting stud or pin 3, on which is rotatably mounted the hub 4 of a wheel 5, this wheel having on that face which is nearest the bar 1 outer and inner 55 circular rows of beveled gear-teeth 6 and 7.

The bar 1 is provided on its forward side or face with a projecting arm 8, on which is carried a short horizontal weaver-tube 9, the latter being formed in the usual manner, as 60 indicated at 10, with a longitudinal recess extending from the periphery to the center of said tube. This tube has fixed in connection with its outer end a gear-wheel 11, which is provided with a recess 12, forming a continuation 65 of the recess 10. The gear-wheel 11 gears with a pinion 13, carried on a horizontal shaft 14, which is supported in suitable bearings on the forward side of the bar 1 and has one of its ends mounted in a rearward 70 extension 1^c of the hinge-cylinder 1^b. The shaft 14 also carries between the arms 1^a of the bar 1 a double bevel-wheel 15, the inclined teeth on one side of which are adapted to gear with the teeth of the inner and smaller row 75 of the wheel 5, while the remaining and opposingly-inclined teeth of said wheel 15 are adapted to gear with the teeth of the outer row 6. The wheel 15 is formed on one side with a tubular hub 15^a, through which passes 80 a set-screw 16. The adjustment of said wheel 15 to positions on the shaft 14 which permit of its engagement with the teeth of the desired row 6 or 7 is effected by loosening said set-screw and sliding the wheel 15 on 85 said shaft 14. For the sake of clearness in illustration the wheel 15 is shown in the drawings as not in gear with either of said tooth-rows.

17 represents a swinging gate or frame comprising vertical side arms 17^a and rearwardly-curved upper and lower arms 17^b, the latter being pivotally mounted on the end of a vertical hinge-pin 18, which extends through the hinge-tube 1^b, which forms the termination 90 of the bar 1. At the junction of the ends of the frame-arms 17 with the ends of said arms 17^a the latter are formed with enlarged terminations in the form of box-like extensions 19, an opening being formed in the outer side 100 of each of these extensions and on the outer side of the arm 17^a, as indicated at 20 in Fig.

3. In the remaining portion of each of these box-like projections is journaled a friction-roller 21.

22 represents a horizontal-fence-wire-engaging frame and weaving-machine gate, which consists of two vertical and parallel inclined bars 24, suitably connected by intervening brackets 25, the outer side of each of said bars 24 being provided on its outer wing 10 or flange with a vertical and forwardly-extending rack 26.

Projecting from the outer side of the gear-wheel 11 from a point eccentric thereon is a wire-spool-carrying pin 27. Upon this pin is 15 adapted to be rotatably mounted a spool of wire 28.

In utilizing our invention the weaver-supporting frame 22 is so arranged with relation to the previously-strung horizontal fence-wires 29 as to cause said wires to engage corresponding teeth of the racks 26, while the inturned flanges of the standards 24 extend loosely, as shown, within the openings 20 at the corners of the frame or gate 17, the rear 25 sides of said standards being thus brought into frictional contact with the friction-rollers 21. It will be observed that the engagement of the horizontal fence-wires with the rack-teeth of the standards 24 will serve to 30 support the frame 22 on said horizontal fence-wires, and the weaving-tube being properly turned to receive in its recess 10 and in the recess 12 of the gear-wheel 11 one of said horizontal wires it will be seen that the support 35 of the tube by said wire, in conjunction with the support given by the operator at the handle, will permit of the weaving-machine being supported in a desirable horizontal position. In this manner one of the horizontal 40 fence-wires, which we will assume is the top wire of the fence, is in position to have engaged therewith the free end of the spool-wire 28. This being accomplished and the weaver-recesses 10 and 12 being turned to 45 permit an outward movement of the machine and disengagement of said wire therewith, the machine is swung outward on the pin 18 and allowed to slide downward on the standards 24 until the tube and gear-wheel recesses 50 10 and 12 are in position for receiving the next horizontal wire of the fence. In this outward-swinging operation it will be observed that sufficient wire will be uncoiled from the spool 28 to give the desired slack or 55 length of cross-wire to reach to the next succeeding horizontal wire. The machine being again swung toward the fence and the second horizontal wire being engaged by the tube and gear-wheel recesses, rotary motion is imparted to the wheel 5 through the medium of a crank, which may be carried upon the shaft 3, and assuming that the double bevel-wheel 15 is in gear with one or the other of the rows 6 or 7 of teeth on the wheel 5 it is obvious 60 that rotary motion will be imparted to the shaft 14, the pinion 13, and gear-wheel 11, 65

which will result in carrying the wire-spool 28 about the adjoining horizontal fence-wire, thus producing a winding engagement with the latter of the wire 28. This being accomplished, the machine may again be thrown outward and dropped to the next wire 29, where the same process of engaging the wire 28 with the horizontal wire 29 may be repeated. It is obvious that when a comparatively slow motion of the machine is desired the set-screw 16 may be loosened and the wheel 15 moved to engage with the tooth-row 7 of the wheel 5, or when a faster motion is desired the wheel 15 may be moved to engage 75 with the outer tooth-row 6.

In Fig. 7 of the drawings we have illustrated means for holding the angle-bars of the frame 22 in connection with the horizontal fence-wires, consisting of the employment of 85 pins 30, which may be removably inserted in oppositely-located openings in the teeth of the racks 26, these pins passing on the outer sides of the wires 29. It will also be understood that in gaining distance longitudinally 90 of the frame 22 may be made to slide on the horizontal wires of the fence to the new positions.

In order to prevent any binding action or undue friction of the angular standards 24 95 with the swinging frame or gate 17, we have provided the journaled friction-rollers 21, with which the rear sides of said standards may contact in the upward or downward movement of said frame.

From the construction and operation which we have described it will be seen that simple, reliable, and effective means are provided for weaving cross-wires in fences of that class which is partially illustrated in 105 Fig. 6 of the drawings.

Having now fully described our invention, what we claim, and desire to secure by Letters Patent, is—

1. In a machine for weaving cross-wires in 110 fences, the combination with a vertically-arranged frame 22 adapted to be slidably supported upon the horizontal wires of a fence, of a main machine-bar 1, a fence gear-wheel journaled in connection therewith and having an inner and an outer row of gear-teeth on 115 its face, a horizontally-journaled shaft in front of said wheel, a pinion-wheel 11 carried on said shaft and a double bevel-wheel 15 slidably mounted on said shaft, a longitudinally-recessed weaver-tube supported from 120 said bar 1, a correspondingly-recessed gear-wheel 11 connected with said weaver-tube, a wire-spool-carrying pin projecting from said gear-wheel, and a swinging connection of the 125 bar 1 with the supporting-frame 22, substantially as specified.

2. In a machine for weaving cross-wires in 130 fences, the combination with a vertically-arranged frame 22 comprising connected angular standards 24 and toothed bars 26 projecting from said standards, of a weaving-

machine comprising a main bar, a recessed weaver-tube projecting therefrom and means for imparting rotary motion to said tube, a frame or gate 17 pivotally connected with one end of said bar, said gate having laterally-recessed corner portions adapted to receive loosely the inturned wings or flanges of said standards 24, and friction-wheels 21

journalized within said gate corner portions, as and for the purpose set forth.

WILLIAM GROVES.
GRANVILLE D. O'DAY.

In presence of—

JOE SHANNON,
R. H. SCHRYVER.
